UNITED STATES PATENT OFFICE.

GEORGE A. EYNON, OF CLEVELAND, OHIO, ASSIGNOR TO THE UNIVERSAL CARBURETOR COMPANY, OF CLEVELAND, OHIO, A CORPORATION OF OHIO.

CARBURETER.

1,181,514.

Specification of Letters Patent.

Patented May 2, 1916.

Application filed October 9, 1913. Serial No. 794,266.

To all whom it may concern:

Be it known that I, GEORGE A. EYNON, a citizen of the United States, and a resident of Cleveland, county of Cuyahoga, and State of Ohio, have invented a new and useful Improvement in Carbureters, of which the following is a specification, the principle of the invention being herein explained and the best mode in which I have contemplated 10 applying that principle, so as to distinguish it from other inventions.

The subject of the present invention is improved apparatus for volatilizing liquids.

One particular use to which the invention 15 will be applied is in the volatilization of liquid fuels for internal combustion engines, and the apparatus is adapted to so perfectly intermix the liquid with air that it is possible to volatilize exceedingly heavy fuels 20 such as kerosene, and even heavier liquids. The advantages of such apparatus will be readily seen in view of the attempts which are being made to find means for utilizing the heavier distillates of petroleum for the 25 purpose of operating internal combustion engines. By thus referring to the use of the present invention in connection with internal combustion engines, I do not mean to limit the same to this use, as many other 30 adaptations of the invention will readily suggest themselves to men skilled in the various arts.

To the accomplishment of the foregoing and related ends, said invention, then, 35 consists of the means hereinafter fully described and particularly pointed out in the claims.

The annexed drawing and the following description set forth in detail certain means 40 illustrating the invention, such disclosed means illustrating, however, but one of various ways in which the principle of the invention may be used.

In said annexed drawing:—Figure 1 is a 45 central vertical section (partially in elevation) illustrating my invention; Fig. 2 is a section of the same on the line 2—2, Fig. 1; and Fig. 3 is a perspective view of a detail of construction.

50 In the volatilization of hydrocarbon fuels for use in internal combustion engines the ordinary carburetor has been developed al-

most entirely for the purpose of volatilizing the lighter distillates, such as gasolene. The present trend of development in this industry indicates that in the near future some means will be required which will operate as efficiently to volatilize kerosene as the present carburetor does gasolene. The greater specific gravity of the kerosene 55 makes the present problem much more difficult than that met with in volatilizing gasolene, and a much better intermixture of the air and fuel is necessary to give equally good and better results. It is to secure this complete and perfect intermixture of the fuel 60 when volatilized and the air that the present apparatus has been developed.

The disclosed apparatus may be considered to include means adapted to form and 65 simultaneously mix with air a number of separated columns of the fuel and next intermix these separate columns of fuel and air. The preliminary mixing or carbureting is secured by setting up eddy currents in the 70 several columns of fuel by means of suitable baffling or choking means.

The preferred form of my apparatus shown comprises a carburetor of the "floatless" type provided with a liquid fuel chamber 50 leading to a mixing chamber 51. The latter is tubular in form being supplied with air through an opening 52 in a lateral extension 53. The conduit 54 which leads from the chamber 50 passes through chamber 51 and is supported on the bottom of the same by a tube 55, threaded to receive an adjustable rod 56 attached to a needle valve 57 at its upper end. Such valve 57 controls the discharge outlet 58 from the 80 conduit 54, the valve being properly adjusted by a knurled nut 59 on the rod 56. The outlet 58 also receives a second valve 85 extending through a cylindrical casing or carbureting chamber 61 attached to the outlet part of the conduit 54. This casing 61 is enough smaller than the mixing chamber proper to permit of some air passing up around it. Such air has two means of outlet, one around a disk 62 resting upon the 90 casing 61, and loosely fitting in the chamber 51 and the other through apertures 63 in such disk when the latter is raised by the suction in the mixing chamber 51. The disk

is integral with valve 60 and is maintained normally in the position shown by a spring 64 operating against a collar or cap 65 supported in the casing.

5 The action of the carbureting chamber is as follows: The casing 61 is provided with a plurality of spaced apertures 66 in its bottom through which the air enters. Larger apertures 67 are formed in the top 10 of the casing, these latter corresponding in number and position to those in the bottom. The liquid passes from the valve 57 laterally and is caught up and carbureted by the air currents forming a number of separate columns 15 of mixed vapor and air. Each column is given a certain internal movement by the size and position of the upper aperture through which it passes, thus preliminarily mixing the carburetant and air. Upon passing through the apertures 67 and the apertures 63 in the disk, the various columns are intermixed, the resulting product being an extremely intimate intermixture of the vaporized liquid and air, the proportions of 20 each being controlled by the relative sizes of the air and fuel supply conduits, as well as to some extent by the proportions of the various apertures in the casing 61.

An auxiliary air valve is provided consisting of an apertured disk 70 normally seating over an opening 71 in the chamber 51. The disk 70 is held down by a spring 72 operating against a collar 73 on a rod 74 adjustably engaged in a yoke 75 attached to 35 the casing 51. The tension of the spring 72 is such that the valve only opens upon a very considerable increase in the vacuum in the chamber 51, it opening only after the disk 62 has been raised.

40 The usual type of throttle control is provided, a butterfly valve 76 being pivoted in the mixing chamber. Below the same is an inlet 77 controlled by a valve 78 which may be connected to a source of fuel such as gasoline for starting purposes.

The foregoing apparatus has been found, from actual tests, to secure an extremely quick atomization, even of relatively heavy liquids, and a practically perfect mixture of 50 the vapor with the air. The various uses to which such apparatus can be applied need not here be enumerated as they will readily suggest themselves to those skilled in the various arts. It may be mentioned, however, that the invention has already been successfully applied to the volitilization of kerosene for use in internal combustion engines, and it is for this reason that the foregoing description has dealt with such an application of the invention as affording the best and clearest illustration of the preferred forms of the apparatus.

The new and improved method of volatilizing liquids of which the use of the im-

proved apparatus herein described and hereinafter claimed is an illustration will form the subject matter of another application for United States Letters Patent.

Having thus shown and described my invention, what I claim and desire to secure by Letters Patent is:

1. In apparatus of the character described, the combination of a mixing chamber; a carbureting chamber communicating with said mixing chamber through a plurality of fuel openings in the upper wall of said carbureting chamber; carburetant and air supply passages communicating with said carbureting chamber, said air passage including a plurality of openings in the lower wall of the carbureting chamber aligned with the aforementioned fuel openings, and said carburetant passage communicating with said carbureting chamber intermediate said air openings; and further air supply means communicating with said mixing chamber.

2. In apparatus of the character described, the combination of a mixing chamber; a carbureting chamber communicating with said mixing chamber through a plurality of fuel openings in the upper wall of said carbureting chamber; carburetant and air supply passages communicating with said carbureting chamber, said air passage including a plurality of openings in the lower wall of the carbureting chamber aligned with the aforementioned fuel openings, but of different area, and said carburetant passage communicating with said carbureting chamber intermediate said air openings; and further air supply means communicating with said mixing chamber.

3. In apparatus of the character described, the combination of a mixing chamber; a carbureting chamber communicating with said mixing chamber through a ring of fuel openings in the upper wall of said carbureting chamber; carburetant and air supply passages communicating with said carbureting chamber, said air passage including a plurality of openings in the lower wall of the carbureting chamber aligned with the aforementioned fuel openings, but of smaller area, and said carburetant passage communicating with said carbureting chamber within the ring of air openings; and further air supply means communicating with said mixing chamber.

4. In apparatus of the character described, the combination of a mixing chamber; a carbureting chamber contained within said mixing chamber and communicating therewith through a plurality of fuel openings in the upper wall of said carbureting chamber; and carburetant and air supply passages communicating with said carbureting chamber, said air passage comprising said main

chamber and a plurality of openings in the lower wall of the carbureting chamber aligned with the aforementioned fuel openings, and said carburetant passage communicating with said carbureting chamber intermediate said air openings, the cross sectional area of said carbureting chamber being less than that of said mixing chamber, whereby air may

pass through said mixing chamber around said carbureting chamber.

Signed by me, this 1st day of October, 1913.

GEORGE A. EYNON.
